UNITED STATES PATENT OFFICE.

PAUL A. MEEHAN, OF NEW CASTLE, PENNSYLVANIA, ASSIGNOR TO AMERICAN DRESSLER TUNNEL KILNS, INC., OF NEW YORK, N. Y., A CORPORATION OF NEW YORK.

DRYING-KILN CAR.

1,386,013.

Specification of Letters Patent.

Patented Aug. 2, 1921.

Application filed April 26, 1920. Serial No. 376,459.

To all whom it may concern:

Be it known that I, PAUL A. MEEHAN, citizen of the United States, and resident of New Castle, in the county of Lawrence and State of Pennsylvania, have invented certain new and useful Improvements in Drying-Kiln Cars, of which the following is a specification.

My present invention consists in an improved car for use in drying kilns and was especially devised for use in moving brick through a continuous drying kiln. The general object of my present invention is to provide a simple and effective car construction for the purpose specified provided with two brick supporting platforms located one above the other, so that the car can be loaded with brick to a height greater than that to which a single stack of undried brick can be piled without danger of the lower brick of the stack being crushed or deformed by the weight of the brick resting on them.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred embodiment of my invention.

Of the drawings:

Figure 1 is a transverse section of a continuous drying kiln with one of my improved cars therein;

Fig. 2 is a sectional elevation, taken at right angles to Fig. 1.

Fig. 3 is a plan view of a portion of the car;

Fig. 4 is an elevation of one of the bolsters; and

Fig. 5 is a section on the line 5—5 of Fig. 3.

The continuous tunnel kiln type of drier A shown by way of example in Fig. 1, comprises an inclosing housing with track rails A' at the bottom of the chamber for the cars B, on which the brick or other material to be dried are moved through the kiln. As shown the drying kiln is heated partly by means of a conduit A² between the track rails through which a heating fluid is passed, and partly by means of hot air injected into the chamber from the distributed

discharge orifices of pipes A³, the latter being supplied with air through valved connections from external supply pipes A⁴. The roof of the kiln chamber is provided at proper points with outlets A⁵ for moist air. These outlets are ordinarily provided with regulating dampers A⁶.

My improved kiln car B comprises a body portion advantageously formed of structural metal, and provided with bearings for the supporting wheels B' which run on the track rails A'. Mounted on and riveted to the car body proper, are a series of transverse bolsters C and C' which unite to form pier like supports for the brick. The bolsters are advantageously so proportioned and spaced apart that each brick in the bottom course, wherein the brick run lengthwise of the car, has its ends resting on two adjacent bolsters. The intermediate bolsters C are each preferably approximately twice as wide as the end bolster C', and each intermediate bolster C supports two sets of brick placed end to end. (See Fig. 5.) Advantageously the bolsters are inclined so that the upper surface of each bolster slopes downward at a slight angle from the outer end of the bolster to its center. The purpose of this tilt is to slightly incline the stacks X of brick one at each side of the longitudinal central plane of the car toward that plane when the brick are in their normal rectangular condition, so that if the brick contract more rapidly at their outer sides or ends than the inner sides in initial stages of the drawing operation, this unequal contraction will not cause the stacks of brick to lean outward from the vertical.

Advantageously the bolsters are formed of metal plate pressed into the hollow form shown in the drawings, and are provided with outwardly extending bottom flanges C², the flanges of adjacent bolsters overlapping in the assembled construction as shown in Fig. 5.

Above the brick supporting platform formed by the bolsters secured to the car body is a second brick platform comprising a supporting frame D advantageously made of structural metal and provided with intermediate and end bolsters C and C', respectively, which may be identical with those mounted on the car body. At each side of the car, the upper platform D is provided with depending legs D'. As shown

100

105

110

there are three of these legs at each side of the car. The legs D' are advantageously made of channel bars as shown and have their lower ends beveled off as shown at the 5 left hand side of Fig. 1 to enter the sockets formed by pocket members E secured to the sides of the car body.

In the contemplated mode of operation of the apparatus shown, the upper supporting 10 platform D is lifted off the car body for the initial loading of the car. After the proper amount of brick are stacked up on the bolsters, C and C' of the car body, the upper supporting platform D is put in place and 15 the proper amount of brick are stacked up on the supporting bolsters C and C' of the platform D. Thereafter the car is moved through the kiln and its brick load is thereby dried. The car is next unloaded by removing first the brick mounted on the upper platform D after which the latter is removed from the car and the brick on the car body are removed. The spaces between 20 the adjacent bolsters C and C' of the car body and on the upper platform D provide channels for the circulation of the kiln atmosphere, thereby facilitating the drying operation. A second function of these spaces is to receive the fingers of brick handling 25 mechanism of known type whereby all or a substantial portion of the brick mounted on the upper platform D, or on the lower platform of the car may be put in place or removed in a single operation. With the brick 30 arranged in stacks X as shown, I contemplate the removal and putting in place of a stack at a time. The hollow form of the bolsters C is advantageous not only because of the economy in weight and cost involved 35 in this form of pressed metal construction, but also because the hollow interiors of the bolsters form ventilating channels open at their under sides and outer ends through which the kiln atmosphere may pass into 40 the stack of brick resting on the bolsters through the apertures C³ formed in the top 45 walls of the bolsters C. Preferably the

brick are stacked to provide vertical spaces or channels in the brick mass open at their lower ends to the apertures C³.

While in accordance with the provisions of the statutes I have described and illustrated the best form of my invention now known to me it will be apparent to those skilled in the art that changes may be made 55 in the form of the apparatus disclosed without departing from the spirit of my invention as set forth in the appended claims and that certain features of the invention may sometimes be used to advantage without a 60 corresponding use of other features.

Having now described my invention, what I claim as new and desire to secure by Letters Patent, is:

1. A car for the purpose specified having 65 a work supporting platform formed by hollow pressed metal bolsters each bolster having its upper surface inclined downwardly at a slight angle from its outer end toward its center.

2. A car for the purpose specified comprising a car body and a work supporting platform formed by a series of hollow parallel metallic bolsters, said bolsters having openings 70 formed in their upper surfaces.

3. A car for the purpose specified comprising a car body having a work supporting platform and a second platform above the first mentioned platform carried by legs detachably connected to the car body.

4. A car for the purpose specified comprising, a car body frame formed with sockets at its sides and provided at its top with parallel spaced apart brick supporting bolsters and a second frame above said car body 85 frame provided with depending legs removably seated in said sockets, and parallel spaced apart brick supporting bolsters mounted on said second frame.

Signed at New Castle, in the county of 90 Lawrence and State of Penna., this 23 day of April, A. D. 1920.

PAUL A. MEEHAN.
